FLORAL RACK

Filed Nov. 24, 1930

UNITED STATES PATENT OFFICE

CLARENCE J. WHITE, OF PEORIA, ILLINOIS

FLORAL RACK

Application filed November 24, 1930. Serial No. 497,732.

This invention has reference to improvements in floral racks particularly of the type for use by undertakers and funeral directors for displaying floral pieces at funeral services.

The invention has for an object, the provision of a rack that while simple in construction and inconspicuous in appearance as is required in such devices, part thereof can be 10 adjusted to different positions with respect to the other part thereof for the best disposal and arrangement of a floral piece carried thereby.

Another object is to provide a rack wherein 15 an upper portion or section of such rack can be supported in a position lying in the same plane with the main portion, or that can be supported in other positions including a horizontal one.

Again, an object lies in the provision of a 20 shelf portion capable of attachment to the rack at any desired position or location for use in the disposal of a floral piece to the best advantage in connection with the whole floral display.

In addition, the invention includes certain 25 features of construction believed to be novel, and which will be pointed out in the following specification and shown in the appended drawing forming part hereof, and wherein:

Figure 1 shows the rack of my invention in perspective.

Figure 2 is a side elevation of the same.

Figure 3 is a plan of a shelf shown in Figures 1 and 2, the same being illustrated in a collapsed flat position as for storage or shipment.

Figure 4 shows in perspective a certain finger arrangement of Figures 1 and 2.

Figure 5 is an end elevation of the same on a larger scale.

Figure 6 shows in perspective parts of a latch arrangement, and

Figure 7 is an end elevation of the same.

The main portion of the rack comprises in this instance a rectangular frame 1 bent into the form of a U, the leg extremities of which are recurved to create supporting feet 1', by preference merely, there being longitudinal 50 ly and laterally extending rods 2 and 3 re-

spectively serving to brace the frame, such lateral rods also serving to support certain portions to be described.

A top supplemental rack portion is provided which in this instance, also, is rectangular in form and comprises a frame 4 braced by rods 5 which may be parallel to the rods 2 of the main rack portion 1, 2, 3, and braced also by lateral rods 6, all of the rods of both rack portions being preferably electrically 60 welded in position at their ends. At least two of the rods 5 extend beyond the limits of one end of the frame 4 and eyes 5' formed thereon take around the upper portion or yoke of the main frame 1 in such manner as 65 to hingedly connect the two rack portions, it being understood, however, that the hinged connection may be otherwise created.

A prop or support is provided for the main 70 rack portion 1 which may comprise a pair of rods 7 connected by cross rods 8, for example, the upper end of each rod 7 having an eye to engage a suitable part of the main rack by taking around a rod 3', for example, thus 75 hingedly joining the thus constructed support to said main rack portion. Any suitable link may connect the support 7, 8 to the said main rack portion. This may be a member 10 taking around one of the rods 3 of the 80 said portion and provided with a hook 11 to engage a part of said support such as a bail 12 or some other portion.

It is the desire to fix the upper or top rack portion 4, 5, 6 at any desired angle with 85 respect to the main portion 1, 2, 3, or in the same plane therewith, and to provide for locating it in a horizontal plane, all to the end that a floral piece mounted on said portion 4, 5, 6 may be disposed in the most advantageous position for display and for its decorative effect, depending upon the form or nature of such floral piece. That any such position may be had there is provided a separate support for such portion 4, 5, 6 which in this instance consists of a pair of rods 13 90 connected by brace-rods 14, the upper ends of the former each having an eye 15 to engage loosely around one of the rods 6 of said portion 4, 5, 6, the other ends of the rods being suitably supported by any one of the rods 8 100

of the support 7, 8, for example, which rods in some of the claims I shall refer to as abutments for the sake of brevity and clarity.

In order to have a form of attaching means 5 that will not be released by accident there is shown in Figures 6 and 7 a U-shaped member 15' to the ends of which the rods 13 are affixed, as by welding, said member 15' being adapted, due to its form, to engage and 10 lie astride any one of the rods 8. Slidable upon the rods 13 is a keeper 16 the parts 17 of which when engaged at one side of the rod 8 effectually prevents separation of the parts named. While I have shown but two posi- 15 tions of the portion 4, 5, 6 it is obvious that the support 13, 14 for the latter may be supported from any one of the rods 8 accord- 20 ing to the position it is desired that the said portion is to have with respect to the main rack portion.

In displaying floral pieces on racks of this type quite often it has been found that certain forms of these pieces can be best shown in a horizontal or substantially horizontal 25 position when massed with flat pieces which are supported in position upon the usual fingers 16' common to some racks. That such pieces can be accommodated in the best manner, therefore, I provide a shelf that can be 30 hung upon some part of the main rack portion 1, 2, 3 at any desired height or location laterally of said portion. Herein, the shelf comprises a frame 17' and bracing rods 18, the extremities of the frame having eyes 19 taking around a rod 20 affixed to a U-shaped frame 21 terminating in hooks 22 which may be hung upon any one of the rods 3 of said main rack portion found most suitable for a given display. The frame 21 lies against the 35 rods 2, 3 and a support consisting of rods 23 braced by rods 24, for example, is hingedly connected at 25 to the frame 21 while the rods 24 at their other ends have eyes 26 slidably engaging certain of the rods 18 of 40 the shelf 17, 18. It is to be understood that the form of the attachment including said shelf may be changed to suit the idea of the manufacturer and that I do not, therefore, confine myself to the exact structure shown. 45 I preferably make the shelf structure, how- 50 ever, so that it can be collapsed and made to lie flat as in Figure 3 for easy storage and shipment. And in this connection it is to be noted that due to the construction of the rack 55 itself, all of the parts shown can be made to lie flat upon each other due to the ability to collapse them.

The fingers 16' mentioned have eyes 16² taking around the rods 3 or 6, as the case may 60 be, and are connected by a rod 16³ which as shown in Figure 5 limits the swinging move- 65 ment of the fingers by engaging the rods 2 or 5 as the case may be.

It is now seen that I provide a rack for 65 the purpose named that has several import-

ant advantages in that various adjustments are possible in providing for mounting and displaying such types of floral pieces that heretofore have been difficult of disposition.

It is customary to entirely cover a rack of this nature with flat pieces by impaling them upon the fingers 16'. Now by providing the shelf 17', 18 herein described the effect of the too extensive blanketing of the rack can be relieved by the placing of other types of floral pieces thereagainst upon said shelf thereby greatly heightening the decorative effect besides best disposing of such types that are somewhat difficult to display properly. Somewhat the same is true in the use 70 of the top supplemental rack portion 4, 5, 6. That is to say, when said portion is disposed at the top of the rack 1, 2, 3 at an angle to the plane thereof, often a stiff appearance 75 of a display can be softened while when said portion is disposed horizontally it is extremely convenient for treating a display in the best possible manner besides admitting of supporting certain forms of pieces that could not otherwise be accommodated, at least to 80 the best advantage. And it is here that the positive latch arrangement 15, 16 is of consider- 85 able value in that there is no chance for a display once set up on the supplemental rack portion to be accidentally disarranged as 90 would result were the support 13, 14 to leave the support 7, 8.

While I use the said support 7, 8 as the portion upon which to rest the support 13, 14, it is to be understood that the latter sup- 100 port may be otherwise held i. e., on any other part of the rack structure. While said sup- 105 port 13, 14 might rest upon the floor its connection with some part of the rack structure is desirable since the complete rack may be 110 easily moved about as a rigid unit.

I claim:

1. In a floral rack, the combination with a main portion presenting a substantially flat front face upon which to dispose floral pieces, 110 and a prop at its rear side for supporting it in an upright position, said prop including members disposed at different heights thereon, of a supplemental substantially flat frame hingedly attached to the said main portion, 115 the plane of which is adapted to lie in the same plane with the said main portion, or at an angle to said portion rearwardly, and a support engaging both the said supplemental frame and part of the prop adapted by an 120 adjustment with respect to the said members of the latter to maintain the said supplemental frame in either of the named positions.

2. In a floral rack, the combination with a 125 main portion presenting a substantially flat front face upon which to dispose floral pieces, and a prop at its rear side for supporting it in an upright position, said prop having a series of members arranged at different 130

heights thereon, of a supplemental substantially flat frame hingedly attached to the said main portion, the plane of said supplemental frame adapted to lie either in the 5 same plane with said main portion or at an angle thereto rearwardly, and a support engaging at one end the said supplemental frame between its ends, and at its other end adapted to engage any one of said series of 10 members and being of a length to maintain the said supplemental frame in its said raised position or in a lowered position.

3. In a floral rack, the combination with a main portion comprising a frame and cross 15 members therefor forming a flat structure presenting a free front face upon which to dispose floral pieces, and a prop connected to the said portion including a series of members each of a different height thereon, said 20 prop supporting the main portion in substantially an upright position, of a supplemental frame hinged at one edge to and terminating the top of said main portion adapted to lie both in the same plane with said 25 portion and to project rearwardly from the same in substantially a horizontal position in the erected position of the rack, and a support extending between the prop and said supplemental frame, hingedly attached to the 30 latter and adapted to be lodged upon one of the members of the prop for supporting the said supplemental frame in a given position.

4. In a floral rack, the combination with a rack structure comprising a main frame including crossed members forming a flat structure presenting a free front face upon which to dispose floral pieces, and a prop hinged to the rear side of the frame for supporting the latter in substantially an upright position, said prop including a series of members 35 at different heights thereon, of a supplemental frame hinged to and terminating the top of the said main frame adapted to lie in the same plane therewith, and also at an 40 angle thereto rearwardly, and a support hinged to said supplemental frame and adapted for selective engagement with the 45 said members of the prop whereby to support said supplemental frame in a given position with respect to the main frame including 50 the position first described.

5. In a latch for holding in connected relation two separable parts of a floral rack, the combination of a member to be supported, 55 a U-shaped member mounted thereon, a supporting member including a part to be received into the said U-shaped member, and a movable latch carried by the first named member adapted to close the opening of the 60 U-shaped member for retaining the supporting member within the latter.

6. In a floral rack, the combination with a supplemental rack portion and a part upon which it is to be supported, said part consisting of a rod of a main rack portion, of a rod 65

carried by said supplemental rack portion, the same having a U-shaped member fixed with respect to it adapted to engage over the said rod of said main rack portion, and a keeper 70 slidably on said rod of said supplemental rack portion, the same having an extension substantially paralleling its direction of sliding movement adapted to engage over the rod of the main rack portion, said member and said keeper enclosing the last said rod. 75

In testimony whereof I affix my signature.
